UNITED STATES PATENT OFFICE.

JOHN W. EDMANDS, OF NEWTON CENTER, MASSACHUSETTS, ASSIGNOR TO CENTRAL RAILWAY SIGNAL COMPANY, OF PITTSBURGH, PENNSYLVANIA, A CORPORATION OF NEW JERSEY.

FUSEE-CAP.

1,103,279.

Specification of Letters Patent. Patented July 14, 1914.

Application filed May 5, 1914. Serial No. 836,583.

To all whom it may concern:

Be it known that I, JOHN W. EDMANDS, a citizen of the United States, residing at Newton Center, in the county of Middlesex 5 and State of Massachusetts, have invented certain new and useful Improvements in Fusee-Caps, of which the following is a specification, reference being had therein to the accompanying drawing.

10 This invention relates to improvements in fusee caps wherein a combined closure for the cap and an internal shoulder or rim is formed within the fusee cap for the purpose hereinafter described, whereby the closure and shoulder or flange are formed integral with the wall of the cap thus constituting a one-piece cap closure and shoulder.

Heretofore a combined closure and shoulder for fusee caps has been made of a wood- 20 plug which is inserted in the end of the fiber or paper tube, constituting the cap, the inner end of the wood-plug having a recess which forms an annular shoulder or flange. These wood-plugs have been fastened with- 25 in the paper or fiber tubes either by means of small tacks driven through the wall of the tube into the wood-plug, or by gluing the plug within the end of the paper tube. The purpose of the wood-plug is three-fold, 30 one being to form a closure for the end of the tube forming the cap; two, the forming of an annular flange or shoulder against which the end of the fusee abuts, thus protecting the primer of the fusee from con- 35 tact with the cap whereby it is liable to be knocked off, the plug and flange serving to stiffen the end of the cap; and third, the outer surface of the plug serving as a receiver for a coating of lighting material 40 complementary to the primer on the fusee, whereby when the cap is removed, the fusee can be lighted by friction between the complementary materials of the cap and the primer of the fusee. It is essential that the 45 plug should not become detached from the cap, and it is essential that the primer should be protected from being knocked off by the cap, for if either the primer or the plug is lost, then the means for lighting the 50 fusee is destroyed.

It is found in practice, that where the closure is a separate element (a plug) from the cap, it at times becomes detached either in shipment or in handling by the train-

man; the small tacks which can be used 55 will become loose and fall out, and the plug lost, or when glue is used the glue may become soft and run down inside of the cap and unite or glue the cap to the fusee, or the soft glue get on the primer, either of 60 which is liable to destroy the efficiency of the fusee; or the glue may dry out and fail to properly hold the plug in place, or the plug is broken away from the single layer of paper forming the cap tube to which it 65 is glued. All of these conditions have, in practice, actually existed, and when they arise, the fusee is practically useless in the hands of the trainman, and this may not be discovered until the trainman attempts to 70 use it and hence too late to get another fusee, or to correct the defect.

The specifications of the Bureau for the Safe Transportation of Explosives, require that the lighting end of the cap be constructed 75 to protect the primer and lighting end of the fusee, and this necessitates the stiffening of the lighting end of the fusee cap, and the provision of a shoulder or flange to hold the primer of the fusee out of contact with 80 the end or plug or closure of the cap.

The primary object of my invention therefore, generically speaking, is to provide a one-piece cap, closure and shoulder—that is, forming the closure and the shoulder 85 from the wall of the paper tube in a manner to meet the requirements of the Bureau for the Safe Transportation of Explosives, and at the same time, absolutely prevent the separation of the lighting end of the cap 90 from the tubular portion, and therefore, overcomes the defects above-mentioned where the closure and flange are formed of an element separate from the tube.

In the accompanying drawings: Figure 95 1 is a central sectional view of a paper tube in position on a mandrel before the operation of closing in the end to form the closure and annular flange. Figs. 1^a, 1^b, 1^c, 1^d, 1^e, 1^f, and 1^g, show how the wall of the paper 100 tube is turned in to finally form the completed closure and flange shown in Fig. 1^g. Fig. 2 shows the tool in its final operation of tightly compressing the closure against the mandrel, and the flange around the reduced end of the mandrel. Fig. 3 is a detached perspective view of the mandrel. Fig. 4 shows the improved cap in position

on a fusee and how the flange protects the primer from contact with the cap.

In producing my improved fusee cap, a paper or fiber tube 1 is placed upon a mandrel 2 and the tube has one end 3 projecting a suitable distance above the mandrel. In Fig. 1 of the drawing the tube is shown as projecting about the proper distance to furnish sufficient of the wall or material to be closed in and form a compact closure 4, and the protecting flange 5, as shown in Figs. 2 and 4. The process of closing in the projecting wall 3 of the tube is a continuibus and uninterrupted process, and is carried out by holding the tube 1 stationary on the mandrel 2 and applying a suitable rotating tool 6 to the end thereof, the tool being so shaped that the wall of the tube is turned inward. Figs. 1^a, to 1^e, inclusive, are simply to illustrate some of the conditions of the wall of the tube during this continuos closing-in process until the final closure and flange is provided as shown in Figs. 1^e and 2 and 4. The mandrel 2 has a reduced end 2^a, forming an annular space 7 into which the inwardly depending turned-in wall 8 (Figs. 1^a, 1^e) is caused to enter during the process of turning-in and closing the tube and in that way the protecting flange 5 is formed. When the turned-in depending wall 8 of the tube has reached the bottom of the annular space 7, as shown in Fig. 1^e, then the further rotating and compressing action of the tool 6 compresses the closure into a substantially solid mass and makes the finished closure and flange which produces a fusee cap having a firm closure such as will meet the specifications of the Bureau for the Transportation of Explosives and, at the same time, form the protecting flange. Preferably, though not necessarily, the reduced end 2^a, is provided with several radiating tapered grooves or recesses 9 to permit the escape of any air which may be caught between the closure and the end of the mandrel down the sides of the reduced end of the mandrel, instead of forcing the air into the folded and compressed closure. These grooves also serve to assist in preventing the rotation of the tube 1 at the time the closure is being compressed, and the greatest compression is exerted thereon by the rotating tool 6. The quality of paper used for making these caps is such that I find the combined closure and flange can be made in the manner shown with the tube dry. However, the tube is preferably subjected to a coating of paste, primarily for the purpose of uniting and holding the folded and compressed closure into its compressed position after the crimping, folding and compressing actions have been performed.

A complementary igniting material 10 is placed on the outer side of the closure 4, and a suitable paper covering 11 incloses the

fusee cap when it is placed on the fusee 12 as shown in Fig. 4, and this paper 11 has its lower edge pasted to the fusee which will hold the cap in position thereon, but enables the cap to be broken away from the fusee when the fusee is to be lighted.

The arrangement here shown for inclosing the cap and uniting it to the fusee and also covering and protecting the complementary igniting material 10, is only one of many ways in which the same result has been accomplished, and is only illustrated for the purpose of conventionally showing the completed fusee with the cap in place thereon. When the fusee is to be used, the cap is detached therefrom and the exposed complementary igniting material 10 is struck or rubbed against the primer 13 and the fusee is lighted, the primer and complementary material being substantially the same chemicals as are used on the heads and boxes of the well-known safety matches.

From the foregoing description and illustration, it will be seen that in my improved fusee cap, the closure and protecting flange are made integral with the tube which absolutely prevents it from becoming detached, as happens with the wood-plug ordinarily used for that purpose, thus accomplishing all of the purposes and functions of the ordinary wood-plug, without any of its defects.

Having thus fully described my invention what I claim and desire to secure by Letters Patent is:

1. A fusee cap comprising a fiber tube having its wall turned inward and formed into a closure for the tube, and a depending annular flange.
2. A fusee cap consisting of a fiber tube having an integral closure and a depending protecting flange integral with the closure.
3. A fusee cap comprising a tube having its wall crimped and folded and compressed inward to form a closure, and a portion of the closed-in wall depending from the closure into an annular protecting flange.
4. The method of closing the end of a fiber fusee cap 2 with a depending annular flange, which consists in first crimping inwardly a portion of the wall of the tube from one end thereof causing it to extend downward within the said tube, folding inward the turned-in portion at a point above the downwardly extending portion, and finally compressing the folded-in portion at a point above the end of the turned-in portion to form a closure and a depending flange.
5. The method of closing the end of a fiber fusee cap with an annular flange depending from the said closure, which consists in crimping inwardly an extending end of the tube and causing it to project downwardly in the form of an annular flange,

folding inward the end of the tube and the
inward downwardly extending flange to
form a closure, and finally subjecting the
folded-in portion to pressure between inner
5 and outer relatively rotatable and stationary
members at a point above the downwardly
extending inner flange.

In testimony whereof I hereunto affix my
signature in the presence of two witnesses.

JOHN W. EDMANDS.
